Primary Examiner — Karen E. Eldridge Powers*Assistant Examiner* — Kimberly Barnes*(74) Attorney, Agent, or Firm* — Banner & Witcoff, Ltd.**CLAIM**

The ornamental design for a display screen with graphical user interface, as shown and described.

DESCRIPTION

The FIGURE is an enlarged front view of a display screen with graphical user interface showing our new design. The long-dash-short-dash outlines showing the display screen and the rectangular shapes inside each of the buttons, as well as the evenly-incremented broken-line features showing text and symbols) are environmental subject matter and form no part of the claimed design.
